[57] CLAIM

The ornamental design for an electrical connector clip
or similar article, substantially as shown.

DESCRIPTION

FIG. 1 is a top plan view of an electrical connector clip
or similar article showing my new design;
FIG. 2 is a bottom plan view thereof;
FIG. 3 is a front elevational view thereof;
FIG. 4 is a rear elevational view thereof;
FIG. 5 is a side elevational view thereof, as seen from
the right side of FIG. 1;
FIG. 6 is a side elevational view thereof, as seen from
the left side of FIG. 1.
